FLYING TARGET

Lynvell R. Jordan, Santa Monica, Calif., assignor
to Jack B. Nethereutt, Los Angeles, Calif.

Application March 9, 1950, Serial No. 148,560

5 Claims. (Cl. 273—105.4)

1

This invention has to do with a flying target and it is a general object of the invention to provide a simple, practical, improved target of the type used in operations commonly referred to as trap shooting or skeet shooting.

The present invention is primarily concerned with a target to be handled or projected by launching apparatus commonly employed in connection with skeet or trap shooting and the target that is provided is characterized by a thin, flat, center portion, round in plan configuration, a curved or bowl-shaped flange B that projects from the periphery of the center, and a rim which is ring shaped and which is joined to or carried by the flange. In accordance with the invention the inner or concave side of the target as formed by the center flange and rim is smooth and plain, being gently curved to conform to the general contour of the structure, and being wholly without sharp or abrupt shoulders, ribs, ridges, or other such characteristics. The exterior of the target is characterized by certain structural features that result from the outer periphery of the flange being joined to one end of the rim at the inside thereof, by the rim being substantially polygonal in cross sectional configuration to have an outer periphery that extends axially of the target, and by a top end which is flat and unobstructed and which occurs in a plane normal to the axis of the target. The center is so joined to the inner periphery of the flange that its outer or top side, which is preferably flat, is inset somewhat from the upper or top end of the target. The exterior of the flange follows the general shape or contour of the flange and is therefore generally spherical in curvature. However, it has a portion of maximum diameter adjoining the rim and extending axially of the target while the remaining portion is stepped to present shoulders which are concentric with the axis of the target and extend parallel with the axis of the target. An outstanding feature of the invention is the construction by which the flange and rim are made practical for handling and launching of the target and yet are so weakened as to readily fail when struck while in the course of flight. The invention provides a series of equally spaced grooves or channels in the exterior of the flange confined strictly to the flange and so formed, shaped, and proportioned as to give the structure the desired characteristics. The rim is provided with corresponding notches or channels which are confined to the outer peripheral portion of the rim.

A general object of this invention is to provide

2

a target of the general character referred to which can be economically manufactured of a material or composition of materials such as are employed in articles of this character and which can be advantageously made within the limits or standards required for targets to be used in connection with skeet or trap shooting.

Another object of this invention is to provide a target of the general character referred to which is so formed and constructed as to have adequate strength to enable it to be easily and practically handled and launched but which, when in flight, is exceedingly fragile and is subject to being fractured when struck by but one pellet from a load of shot such as is used in skeet or trap shooting.

It is a further object of this invention to provide a target of the general character referred to practical for shipment and handling, which is such that it can be thrown or put into flight by conventional launching apparatus and which has weakened points established as by grooves or notches which materially weaken it when in flight, and make it subject to being readily fractured, while at the same time having little or no influence upon the desired flight characteristics.

The various objects and features of my invention will be fully understood from the following detailed description of a typical preferred form 30 and application of my invention, throughout which description reference is made to the accompanying drawings, in which:

Fig. 1 is a perspective view of the target provided by the present invention showing it from 35 what will be termed the top and from one side. Fig. 2 is a top plan view of the target. Fig. 3 is a side elevation of the target. Fig. 4 is a reduced bottom view or elevation and Fig. 5 is a detailed transverse sectional view taken as indicated by line 5—5 on Fig. 2.

The target provided by this invention is preferably a unitary or integral body of suitable material such as the composition or mixture commonly used in the manufacture of articles of this 45 general character. For purpose of example the target may be considered as being formed of a composition embodying or including about 65% limestone and about 35% coal tar.

The article as provided by this invention is characterized, generally, by a center A, a flange B, and a rim C.

The center of the target is located at what may be termed the upper or top portion of the target and is preferably in the nature of a flat round disc of uniform wall thickness. The center is

preferably located in a plane which is normal to the central axis of the target.

The flange B of the target is joined to and projects from the periphery of the center to be concentric with the center and it is preferably curved to be somewhat bowl-shaped. In practice the flange may vary in wall thickness at various parts and may, in general, be spherically curved. The inner peripheral portion 10 of the flange is somewhat inwardly turned or deflected and is the part of the flange to which the center A is connected, and it supports the center in a plane somewhat below or inward of the uppermost part or edge 11 of the target. In the particular form of the invention illustrated the flange B is of minimum wall thickness adjacent the part 10 and it increases somewhat in wall thickness as it extends radially outward and axially to the outer peripheral portion 12, which is joined to the rim C.

The outer wall or face 13 of the outer peripheral portion 12 is curved and is concentric with the axis of the target and extends a substantial distance axially of the target. The wall or face 14 of the flange B, which extends between the face 13 and the innermost portion of the flange is convex and may be substantially uniform in curvature as shown throughout the drawings. In accordance with the present invention several rib-like projections or steps 15 are provided on the convex face 14 of the flange and each step is so formed as to have an outer face 16 curved concentric with the axis of the target and extending axially of the target and a flat face 17 which is in a plane normal to the longitudinal axis of the target. The several steps 15 vary in diameter and in the case illustrated there are three such steps.

The rim C is a ring-shaped element substantially polygonal in cross sectional configuration. In the preferred formation the rim C has a flat upper end 20 which occurs in a plane normal to the axis of the target and which adjoins the face 13 of the flange B and projects radially outward therefrom. The rim has an outer face 22 which is curved and which is concentric with the axis of the target and extends longitudinally or axially of the target. The face 22 establishes the maximum diameter of the target. The lower or bottom end face 24 has a downwardly projecting convexly curved rib 24a adjoining the inner periphery of the rim C, as shown in Fig. 5 of the drawings. The inner wall or face 25 of the rim is pitched and extends upwardly and inwardly from the rib 24a at bottom face 24 so that the rim is somewhat thicker radially where it joins the flange than it is at the lower end of the target. In accordance with the invention the large or outermost end portion of the flange B joins the upper inner corner portion of the rim C in the manner clearly illustrated in Fig. 5 of the drawings.

A series of grooves or lines of weakening is established in the flange portion B of the target. In the preferred construction the grooves or notches 30 that weaken the flange C are equally spaced around the target and they are of such number as to be about 30° apart. The several notches 30 extend continuously from the uppermost point 11 of the target to the point where the wall 13 joins the top 20 of the rim and it is preferred that each notch be substantially uniform in width and depth throughout its length. In a target which is about 4 1/4 inches in diameter, this being the size common for targets of this

type, it is preferred to proportion the various parts about as shown in the drawing, in which case the notches 30 are made about 1/8 of an inch deep in the wall or face 14 of flange B, and are about 1/8 of an inch in width.

The invention provides a series of notches 40 in the rim C of the target and it is preferred that the notches 40 be made to correspond in number and arrangement with the notches 30 so that there is a notch 40 in the rim radially outward of each notch that occurs in the flange. The notches 40 may, in practice, correspond in width and depth with the notches 30 and they preferably extend the entire length of the rim, that is, from the top end 20 to the bottom end 24.

From the foregoing description it will be apparent how the present invention provides a structure the exterior of which is such as appears in Figs. 1, 2 and 3 of the drawings. An important feature of the invention is the shape or configuration of the interior of the target, and from Fig. 5 of the drawings, it will be apparent how the several elements or features of the target may be joined or related so that the inner surface or wall of the target is plain and smooth throughout, being entirely free of sharp ridges, ledges, or protuberances likely to interfere with stable flight and proper operation of the target.

It is to be understood that the various features of the target as hereinabove described may, in practice, be slightly pitched or modified in order to provide drift enabling the target to be economically molded, for example, in practice the notches 30 and 40 are not necessarily angular or sharp cornered, but the sides may be made to converge inwardly somewhat and the bottoms may be slightly rounded.

From the foregoing description it will be apparent that the invention has provided a target conforming, generally, with standards followed in the manufacture of articles of this type, while at the same time the target, when spinning and in flight is highly vulnerable to impact. It has been found that impact representative of about one and one half pellets is necessary to break an ordinary target in flight, whereas impact corresponding to about one half a pellet is all that is necessary to fracture the target of the present invention. In spite of the vulnerability to fracture the target of the present invention is such that it can be handled economically and with minimum breakage and can be operated from usual launching equipment without undue breakage.

Having described only a typical preferred form and application of my invention, I do not wish to be limited or restricted to the specific details herein set forth, but wish to reserve to myself any variations or modifications that may appear to those skilled in the art and fall within the scope of the following claims.

Having described my invention, I claim:

1. A target of the character described having a unitary friable body with a substantially flat disc-shaped center, an annular flange joined to the periphery of the center and extending radially and axially therefrom, and an annular rim joined to the outer periphery of the flange and projecting axially therefrom, the exterior of the flange being substantially convex in form and having circumferentially spaced radially disposed notches of substantially equal width and depth therein extending continuously from where the flange joins the center to where the flange joins the rim and rendering the flange

subject to disintegration when struck, the exterior of the flange having annular ribs thereon in stepped relation and concentric with the flange and the interior of the flange being smoothly curved.

2. A target of the character described having a unitary friable body with a substantially flat disc-shaped center, an annular flange joined to the periphery of the center and extending radially and axially therefrom, and an annular rim joined to the outer periphery of the flange and projecting axially therefrom, and having circumferentially spaced longitudinally disposed notches in the outer periphery thereof, the exterior of the flange being substantially convex in form and having circumferentially spaced radially disposed notches of substantially equal width and depth therein extending continuously from where the flange joins the center to where the flange joins the rim and rendering the flange subject to disintegration when struck, the exterior of the flange having annular ribs thereon in stepped relation and concentric with the flange and the interior of the flange being smoothly curved.

3. A target of the character described having a unitary friable body with a substantially flat disc-shaped center, an annular flange joined to the periphery of the center and extending radially and axially therefrom, and an annular rim joined to the outer periphery of the flange and projecting axially therefrom, and having circumferentially spaced longitudinally disposed notches in the outer periphery thereof, the exterior of the flange being substantially convex in form and having circumferentially spaced radially disposed notches of substantially equal width and depth therein extending continuously from where the flange joins the center to where the flange joins the rim and rendering the flange subject to disintegration when struck, the exterior of the flange having annular ribs thereon in stepped relation and concentric with the flange and the interior of the flange being smoothly curved, the notches in the flange and the notches in the rim corresponding in number and circumferential positioning.

4. A target of the character described having a unitary friable body with a flat disc-shaped center of substantially uniform wall thickness, an annular bowl-shaped flange having its inner periphery joined to the outer periphery of the center inset therefrom, the exterior of the flange being substantially convex in form, and a rim with a flat top parallel with the center and an outer periphery extending straight axially of the target, the upper inner portion of the rim

being joined with the outer periphery of the flange, there being circumferentially spaced continuous notches of substantially equal width and depth in the exterior of the flange extending radially of the target, the ends of the notches occurring at the inner and outer peripheries of the flanges, and there being circumferentially spaced notches in the outer periphery of the rim and extending longitudinally of the target, the notches in the rim being in alignment with the notches in the flange longitudinally of the target.

5. A target of the character described having a unitary friable body with a flat disc-shaped center of substantially uniform wall thickness, an annular bowl-shaped flange having its inner periphery joined to the outer periphery of the center inset therefrom, the exterior of the flange being substantially convex in form, a rim with a flat top parallel with the center and an outer periphery extending straight axially of the target, the upper inner portion of the rim being joined with the outer periphery of the flange, and annular ridges in stepped relation on the exterior of the flange and concentric therewith, there being circumferentially spaced notches of substantially equal width and depth in the exterior of the flange extending straight radially of the target and from the inner periphery of the flange to the rim, and there being circumferentially spaced continuous notches in the outer periphery of the rim and extending longitudinally of the target, the inner surfaces of the center, flange and rim being smooth and faired one into the other, the notches in the flange and the rim being of substantially like size and shape and the notches in the rim being spaced 30° apart and corresponding in spacing and circumferential arrangement with the notches in the flange.
